THE COLUMBIA PLANOGRAPH CO., WASHINGTON, D. C.

UNITED STATES PATENT OFFICE.

JOHN J. MESERLI, OF KINGSVILLE, TEXAS, ASSIGNOR OF ONE-HALF TO FRED F. MILLER, OF KINGSVILLE, TEXAS.

BURNER.

1,188,806.

Specification of Letters Patent. Patented June 27, 1916.

Application filed May 18, 1915. Serial No. 28,949.

To all whom it may concern:

Be it known that I, JOHN J. MESERLI, a citizen of the United States, residing at Kingsville, in the county of Kleberg and State of Texas, have invented certain new and useful Improvements in Burners; and I do hereby declare the following to be a full, clear, and exact description of the invention, such as will enable others skilled in the art to which it appertains to make and use the same.

The invention relates to improvements in burners.

The object of the present invention is to improve the construction of burners and to provide a simple, practical and comparatively inexpensive burner of strong and durable construction designed for use in coal and wood stoves and adapted to be readily applied to and removed from the same and capable of burning all kinds of liquid fuel with safety.

A further object of the invention is to provide a burner of this character adapted to furnish a hot blue blaze without soot or smoke and capable of obtaining a maximum amount of heat at the expenditure of a minimum amount of fuel.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction may be resorted to without departing from the spirit or sacrificing any of the advantages of the invention.

In the drawing Figure 1 is a plan view of a burner constructed in accordance with this invention, Fig. 2 is a longitudinal sectional view of the same, Fig. 3 is a transverse sectional view, Fig. 4 is an enlarged detail horizontal sectional view illustrating the arrangement of the valves for controlling the supply of fuel to the burner and to the starting tube or supplemental burner, Fig. 5 is a detail sectional view illustrating the construction of the filter casing.

Like numerals of reference designate corresponding parts in the several views of the drawing.

In the accompanying drawing in which is illustrated the preferred embodiment of the

invention, 1 designates a cylindrical casing constructed of cast metal or other suitable material and provided at the top with a plurality of transverse slots 2 located at the front and rear portions of the casing at suitable intervals. The casing is designed to be mounted within the fire box of a wood or coal stove and the slots are located below and adjacent to the lids of the stove so that the gas which is ignited at the slots as herein-after fully explained is adapted to intensely heat the stove. The front and rear series of transverse slots are spaced apart and the casing is provided at the space between the series of slots with a row of perforations 3 and short grooves 4 extending laterally from the perforations. The gas ignites at the perforations which produce a line of flame for connecting the flames at the front and rear portions of the casing. The cylindrical casing is provided with front and rear heads 5 and 6 which are preferably in the form of caps as shown and the rear head is provided with a central socket 7 receiving and supporting a reduced closed end 8 of a longitudinal mixing tube 9 extending into the casing from the front thereof through an opening 10 in the front cap 5 as clearly shown in Fig. 2 of the drawing. The mixing tube 9 which is open at its outer or front end 11 is also provided thereat with perforations 12 and it is equipped with a longitudinal series of depending jet tubes 13 which discharge the gas downwardly against the lower portion of the casing and the sides of the cylindrical casing cause the gas to flow upwardly to the transverse slots and the perforations. In order to maintain the depending jet tubes in a relatively cool condition the cylindrical casing is equipped with longitudinal air tubes 14 piercing the ends of heads of the casing and open exteriorly thereof for the passage of air through the said tubes 14 which are imperforate and do not permit the passage of air to the interior of the casing.

Fuel is supplied to the burner through a feed tube 15 consisting of hollow wire and provided at the front with a controlling valve 16 and connected at the rear end with one end of a transverse filter 17 which extends across the rear end of the casing and communicates at its other end with a generating tube 18. The filter 17 which is provided with a plug 19 to afford access to its

interior is designed to be provided with any suitable filtering material such as fine wire for catching the dirt to prevent the same from passing to the burner. The generating tube is connected at its front end with valves 20 and 21 for controlling the supply of fuel to the burner and to an auxiliary burner or starting tube 22 located at one side of the generating tube and adapted to heat the same in starting the burner. The auxiliary burner which is provided at intervals with transverse slots for the ignition of gas has air inlet openings 24 at its front portion. The valve 21 which has a threaded adjustment at 25 may be of any desired construction and it permits the flow of the liquid fuel into the tube 22 and as it burns it heats the tube 22 and the generating tube 18. As soon as the generating tube is heated sufficiently to form gas to start the burner the valve 21 is cut off or closed. The valve 21 is provided with a tube 26 extending into the auxiliary burner or starting tube and receiving the stem 27 which carries a tapered plug 28 but any other suitable type of valve may be used. The valve 20 is of the needle type and the vaporized fuel discharged into the open end of the mixing tube 9 commingles with the air and thoroughly mixes with the same both in the tube 9 and while passing through the depending jet apertures and upwardly to the slots or apertures where it is ignited. The valve 20 is supported by a projecting bracket or plate 29 extending from the open end of the tube 9 and provided with a perforation 30 receiving a projection or lug 31 of the valve 20.

A suitable drip pan 32 is located beneath the casing to catch any drip of the fuel and the tubes and the auxiliary burner or starting tube are supported by suitable braces 33 extending upwardly from the drip pan and secured to the same and to the tubes 15, 18 and 22. The cylindrical casing is seated in the drip pan and in practice the valves will be located exteriorly of the adjacent wall of the stove, it being designed to provide a wall or portion to take the place of the usual stove door where the burner is inserted. Also in practice it is designed to connect a plurality of the burners with a tank or reservoir located exteriorly of a building and any suitable pressure such as air or water pressure may be employed for forcing the fuel through the pipes to the burners to be

supplied. The device is applicable to various types of stoves and when it is removed from the same the stoves may be used for the burning of wood or coal. Various kinds 60 of liquid fuel may be used in the burner without danger and with perfect safety whether the oils are mixed or otherwise.

What is claimed is:

1. A burner of the class described including a cylindrical mixing chamber provided at the top with transverse slots located at the front and rear portions of the casing, said casing being also provided between the series of slots with apertures arranged at 70 intervals, a mixing tube extending into the casing and provided with jet tubes extending downwardly and means for controlling the supply of fuel to the mixing tube.

2. A burner of the class described including a casing forming a mixing chamber and provided at the top with apertures, a supply tube located at one side of the casing and extending along the same, a generator tube extending longitudinally of the opposite side of the casing and communicating at one end with the feed tube or supply tube, inner and outer valves connected with the other end of the generator tube, the inner valve being arranged to supply the casing 85 with fuel and a supplemental burner tube connected with the other valve and extending along the generator tube, said auxiliary burner tube being provided at intervals with transverse slots located in the upper portion 90 of the said auxiliary burner tube.

3. A burner of the class described including a casing forming a mixing chamber and provided at the top with apertures, a feed tube located at one side of the casing, a generator tube located at the opposite side of the casing and communicating at one end with the feed tube, a mixing tube extending into the casing and open at its outer end, a bracket or brace projecting from the open 100 end of the said mixing tube and a valve connected with the generator tube and interlocked with the bracket or brace, said valve being arranged to discharge into the mixing tube.

In testimony whereof I affix my signature in presence of two witnesses.

JOHN J. MESSERLI.
